UNITED STATES PATENT OFFICE.

JOHN ALOYSIUS DOWD, OF FALL RIVER, MASSACHUSETTS.

THREAD-CUTTER.

1,085,026.

Specification of Letters Patent. Patented Jan. 20, 1914.

Continuation in part of application Serial No. 714,889, filed August 13, 1912. This application filed January 15, 1913. Serial No. 742,212.

To all whom it may concern:

Be it known that I, JOHN A. DOWD, a citizen of the United States, and a resident of Fall River, in the county of Bristol and 5 State of Massachusetts, have invented a new and Improved Thread-Cutter, of which the following is a full, clear, and exact description.

This invention relates to improvements in 10 thread cutters, and is adapted to be used with various forms of cutter attachments, as for instance, preferably with the form of attachment disclosed in my co-pending application entitled Thread cutting attachment, 15 filed August 13, 1912, and bearing Serial No. 714,889, of which this case is a continuation in part.

The object in view is to provide a thread cutter which may be driven at various 20 speeds without affecting the quality of thread produced so a maximum speed may be maintained without injury to the threads being cut.

Another object of the invention is to form 25 a cutter either cylindrical and scalloped so that a straight even thread may be cut, or a thread having beveled portions may be cut, the beveled portions of course representing what is known as threaded nipples when 30 severed from a tube in which they are cut.

A still further object of the invention is 35 the provision of a rotating round or scalloped cutter formed with teeth set at an angle whereby the cutter may be set at an angle to the bar being cut less than a right angle, such positioning of the cutter causing the cutting teeth to more easily follow the threads and thereby avoid stripping.

A further object of the invention is to 40 provide a cutter having a flat face which may be ground off whenever the cutting teeth are rounded or dulled in order to present a new or sharp engaging portion.

In carrying out the objects of the invention, 45 the cutters may be mounted in any suitable attachment for rotating the same at any speed and for associating two or more together, if desired. Cutters are made round, or substantially round, and those 50 made substantially round are scalloped in order that when the same are rotated at a certain speed in relation to the tube or bar being cut, a beveled thread will be produced.

In ordinary cutters the thread extends parallel with the axis except the usual pitch,

but in the present invention one form of the device is arranged with threads positioned at an angle to the axis so that the axis of the cutter may be set at a less angle than a right angle to the bar or tube being cut. In 60 addition to these advantages, the cutter may be made perfectly flat so that the same may be ground off whenever the teeth become dull.

A practical embodiment of the invention 65 is represented in the accompanying drawings forming a part of this specification, in which similar characters of reference indicate corresponding parts in all the views.

Figure 1 is a top plan view of a cutter and 70 a fragmentary view of a pipe, the cutter embodying one form of the invention; Fig. 2 is a front view of the structure shown in Fig. 1; Fig. 3 is an edge view of the structure shown in Fig. 1; Fig. 4 is a view similar 75 to Fig. 1 except that the same shows a slightly modified form of the invention; Fig. 5 is a rear view of the structure shown in Fig. 4; Fig. 6 is an edge view of the structure shown in Fig. 4; Fig. 7 is a further slightly modified form of the invention 80 to that disclosed in Fig. 4; Fig. 8 is a rear elevation of the structure shown in Fig. 7; and Fig. 9 is an edge view of the structure shown in Fig. 7.

Referring to the accompanying drawings by numerals, 1 indicates an ordinary tube which is designed to be threaded, and 2 the threading tool or cutter mounted upon a suitable shaft 3 and held in position thereon 90 by any desired means, as for instance key 4. This cutter may be made cylindrical or may be made substantially round and provided with a plurality of scalloped cutting threads or teeth 5 in order to cut a beveled nipple 95 6 on the pipe or tube 1. It will, of course, be evident that a thread could be cut on a solid bar or other article as well as a pipe. The point on each scallop 5 farthest from the center is designed to cut the deepest 100 thread so that the nipples 6 may be tapered, the taper being regulated by the ratio of speed between pipe 1 and the cutter 2. If the cutter is arranged to revolve one thread while the cutter is advanced bodily forward 105 a distance of two threads to one revolution of the tube 1, the bevel of the finished nipple 6 will be twice the distance from the extreme top of each scallop to the extreme bottom of the scallop. If desired each of 110

the scallops 5 could be spaced apart which would result in allowing the cutter to cut any desired taper and have any desired length of unthreaded portion between the 5 opposite ends of a particular nipple. If the cutter 2 was held stationary, that is, against rotation, but fed forward, an ordinary straight thread would be made on the pipe 1. It will be understood that in order to 10 vary the taper of the thread on the nipple 6, the cutter 2 and pipe 1 must be rotated at certain speeds and the cutter 2 advanced longitudinally of the pipe 1 at a certain speed. When this ratio is changed there 15 will be a difference in the thread cut. If it is desired, for instance, to have a long taper, the rotation of the cutter 2 is retarded but the cutter 2 is advanced longitudinally of the tube rapidly, while tube 1 may be rotated rapidly or at a speed in proportion to the speed of the advancing cutter.

In Figs. 4 to 6 is seen a slightly modified form of the invention, in which the cutters 2 are provided with threads or teeth 7, set 25 at an angle to the axial line of the cutter, whereby the cutter may be set at an angle to the pipe 1 which is less than a 45° angle. This is intended to cause the cutter to more correctly follow the threads which are cut 30 and to prevent the stripping of the cut threads. The rotation, the advancing, and the retarding of the cutter is to be accomplished in the same way as in the first structure shown in Figs. 1 to 3. The rotation and the advancement of the cutters, together 35 with the way the same are mounted, is clearly shown in my co-pending application above referred to, but such mounting may be varied or changed as desired, as any suitable 40 mounting which will hold the cutters properly in place and advance the same as desired, will be sufficient.

In Figs. 7 to 9 will be seen a further slightly modified form of the invention, in 45 which the cutting face of the cutter 2' is at right angles to the threads 7' and preferably perfectly flat so that the same may be ground off whenever any of the threads 7' become dull in order to provide a new cutting face. It will be noted from Fig. 9 that 50 this form of cutter does not fit entirely the threads which have been cut, but operates principally from the front end of the cutter. In the other forms of the cutter it will be 55 observed that the threads of the cutter fit for their full length against the various threads which have been cut.

From the various forms of the invention 60 above described and shown in the drawings it will be noted that a thread cutter having scalloped teeth is utilized in order to readily provide threaded nipples with any desired taper. It will also be noted that the cutter may have the threads set at an angle so that 65 the cutter itself may be set at a different

angle from the usual right angle position of the cutters to a more acute angle while cutting the usual thread. This structure is intended to prevent the usual stripping of threads when the machine is being run comparatively fast. Either the cutter having the threads extending substantially longitudinally thereof or at an angle thereto may be formed with curved cutting teeth for fitting the particular pipe being cut, or may 70 be formed with straight teeth extending substantially at right angles to the face of the cutter so that the same may be ground off whenever desired for sharpening purposes. In arranging the cutters, one or more may 75 be used, a convenient number being three when it is desired to cut the nipples with considerable speed. In assembling more than one cutter for cutting the same nipple, it is preferable to arrange like cutters in 80 groups so that they will all act substantially in the same way, and thus more easily follow 85 each other.

The expression "scalloped threads" or "scalloped portions" having threads thereon, is intended to cover rounded peripheral projections or toothed or pointed projections which have straight sides, or in fact any form of projection which rises from a given point gradually to the apex and then descends more or less gradually at an opposite angle to a point an equal distance from the center as the first mentioned point.

Having thus described my invention I claim as new and desire to secure by Letters 100 Patent:—

1. In a cutter of the class described, a substantially round body portion having a scalloped threaded periphery.

2. A cutter comprising a substantially 105 disk shaped body having cutting threads arranged on the periphery extending in a general direction parallel with the axis of the cutter, the threads being inclined sufficiently to give the proper pitch.

3. A cutter comprising a substantially 110 round body portion formed of one piece and having a threaded periphery, the threads on said periphery extending substantially parallel with the axis of said cutter, and inclined only sufficiently for giving the desired pitch, all of said threads being curved for fitting a predetermined sized article to be threaded.

4. A cutter formed from a single piece of 115 material comprising a body portion, and banks of cutting teeth arranged on the periphery of the body portion, each of said banks of teeth being substantially A-shaped, so as to cause the cutter to produce a tapering thread.

5. A cutter comprising a substantially 120 cylindrical body provided with cutting threads on the periphery, said cutting threads being arranged in series and each series being ar- 125

- 5 ranged so that the threads thereof will be arranged progressively at a greater distance from the center and then progressively at a less distance from the center so that as the cutter rotates in operation and is advanced, a tapering thread is produced, the taper agreeing with the speed of advancement and the rotation of the article being threaded.
- 10 6. In a device of the character described, a substantially circular cutter formed of a single piece of material having cutting

threads arranged on the peripheral face in banks or sections with the abutting points of each section farther from the center of the cutter than the remaining points of said banks or sections. 15

In testimony whereof I have signed my name to this specification in the presence of two subscribing witnesses.

JOHN ALOYSIUS DOWD.
